CONTROL CIRCUIT FOR MOTORS

Robert J. Lincoln, Westfield, N.J., assignor to Square D Company, Detroit, Mich., a corporation of Michigan

Filed Mar. 31, 1958, Ser. No. 725,028

9 Claims. (Cl. 318—262)

This invention relates to motor control systems for direct current motors. The system is particularly adaptable to those uses wherein a load is hoisted and lowered and wherein hoisting movement of the load is limited when it has been hoisted beyond a certain position.

A specific example of such use is in a hoist where a load is hoisted during hoisting rotation of the armature of a direct current motor and lowered during lowering rotation of the armature and wherein hoisting of the load beyond a certain position is limited by a limit trip switch to prevent hoisting the load into the hoist supporting structure.

Various systems are safely in operation to control hoist motors so that safe hoisting and lowering of the load at safe speeds and for safe distances is obtained. These systems include limit switches and motor control circuits. An example of a prior system is described in Patent No. 2,515,612, issued July 18, 1950, to H. J. Rathbun and entitled "Motor Control System."

In a control system of the above identified patent, hoisting into the limit switch automatically trips the limit switch and applies a dynamic braking circuit to the motor to stop hoisting movement thereof. A resistor was used to limit the lowering speed of the motor out of the tripped limit switch. In order to obtain adequate dynamic braking when hoisting into the limit switch a compromise in the value of the resistor was used, thus limiting the value of retarding torque that could be obtained when lowering out of the tripped limit switch.

In the present invention a rectifier circuit is used in place of the resistor to effectively provide the necessary motor circuit conditions to insure full dynamic braking when hoisting into the limit switch and to provide increased retarding torque and the resulting slow speed when lowering out of the tripped limit switch.

In view of the foregoing, one of the objects of the present invention is to provide the necessary motor circuit conditions to insure full dynamic braking when hoisting into a limit switch and to provide slow speed while lowering out of the tripped limit switch.

Another object of the present invention is to provide a motor control system with an improved circuit to connect a direct current motor for rotation in a hoisting direction, to set up a full-powered dynamic-braking circuit when the hoisting movement has passed a certain position, and to prepare the motor circuit for lowering rotation after it has passed that certain position.

A further object is to provide a slow speed series motor lowering connection for lowering a hoist out of an over-hoist limit switch zone without requiring the use of an additional electromagnetic switch or relay, or an additional contact on the limit switch and which includes improved means including a rectifier circuit for eliminating any sudden changes in speed which would subject the hoist mechanism and motor to severe shocks and strains.

A more specific object is to provide a slow speed series motor connection in a dynamic braking hoist controller

by causing an armature shunt circuit including a unidirectional resistance to become effective to limit the lowering speed to a safe value while lowering out of the limit switch zone, as the result of opening at least one of the usual normally closed contacts of an overhoist limit switch.

The above objects and others are provided by a motor operating system having a first circuit, which, when energized by a source of energy directs current through the motor armature in a hoisting direction and through the motor field winding in a forward direction in series to cause hoisting rotation of the armature. Upon deenergization of the first circuit by hoisting into a limit switch, a second circuit becomes effective to dynamically brake the armature by directing current, generated by continued rotation of the armature in the hoisting direction after such deenergization of the first circuit, through the armature in a lowering direction and through the field winding in the forward direction. The system also includes a third circuit which, when energized by the source of energy, directs current through the armature in the lowering direction and through the field winding in the forward direction to effect safe lowering rotation of the armature at a slow speed. This third circuit includes a unidirectional or rectifier circuit shunting the armature.

The effective resistance of a rectifier to the flow of current therethrough in its conductive direction is related to the voltage across the rectifier, the resistance being higher when the voltage is low. Thus the rectifier circuit constitutes a high resistance, if not effectively an open circuit, shunting the armature when the voltage across the armature is low to cause the armature to rotate at a slow speed with an unloaded hook. Further, the resistance of the rectifier circuit shunting the armature decreases as the voltage across the armature increases, thereby limiting the armature rotational speed to a safe speed and in the event of an overhauling hook load. The system further includes suitable switches common to the rectifier and other circuits to selectively energize those circuits so that an operator has adequate and safe control over the operation of the hoist at all times, even if he has hoisted into a limit switch. If the operator accidentally hoists into a limit switch, the limit switch is tripped, a dynamic braking circuit is established to retard hoisting movement of the armature and the circuits are prepared for safe lowering out of the tripped limit switch.

An embodiment of the invention as applied to a hoist is more fully described herein by way of example and not of limitation, the description being accompanied by the attached drawing in which:

Fig. 1 is a wiring diagram of the hoist motor operating system incorporating one embodiment of the present invention;

Fig. 2 is a diagrammatic representation of a motor, limit switch, and drive used in a hoist;

Fig. 3 is a wiring diagram of an alternate embodiment of the invention which may be substituted for the embodiment incorporated in Fig. 1;

Fig. 4 is a graph illustrating the resistance and current-conductive characteristics of a rectifier in its conductive direction.

Referring to Figs. 1 and 2, a direct current motor comprising an armature 10 having brush terminals 10a and 10b and a series type field winding 11 having terminals 11a and 11b is arranged to be energized from direct current power supply conductors 12 and 14 for hoisting and lowering a load holding device, such as hook 15 suspended from a cable drum 16 driven by a motor through suitable gearing 18. For operation of the motor in the hoisting direction electromagnetic switches having operating coils 19 and 20 are arranged to connect, through their respective main contacts 19m and 20m the arma-

ture 10, the field winding 11, and the operating winding 21 of a spring applied electromagnetically released brake (not shown), and an acceleration and a speed-adjusting resistor 22 in series with each other across the supply conductors 12 and 14. It is noted that the acceleration and speed-adjusting resistor 22 provides a rheostatically variable voltage source at the motor and between the line 12 and the field terminal 11b during at least certain operations of the motor. It is also noted that, during hoisting of the hook 15, current flows through the armature 10 in the hoisting direction and through the field winding 11 in a forward direction.

Overhoisting or hoisting the hook 15 too closely to hoisting drum 16 causes the hook block 15' to engage a limit switch 29, which is provided with a pair of normally closed contacts 29a and 29b and a pair of normally open contacts 29c and 29d. Hoisting the hook block 15' into the limit switch 29 causes the limit switch 29 to open the normally closed contacts 29a and 29b and to close the normally open contacts 29c and 29d.

Referring again to Fig. 1, contacts 29a are in series with contacts 19m, contacts 29b interconnect terminals 10b and 11a, and contacts 29c interconnect terminals 10a and 11a. Opening of the contacts 29a of the limit switch 29 disconnects the armature terminal 10a from the supply conductor 12, and opening of the contacts 29b interrupts the usual connection between the armature terminal 10b and the field terminal 11a. Closure of the contacts 29c and 29d completes a dynamic braking circuit for the motor from the armature terminal 10a through the contacts 29c to the field terminal 11a, thence through the field winding 11 from the terminal 11a to the terminal 11b, thence through a rectifier R1, a resistor 37 from one end 37a to its other end 37b, and finally through the contacts 29d, to the armature terminal 10b. During dynamic braking, current flows through the armature 10 in the lowering direction and through the field winding 11 in the forward direction. A rectifier R2 is connected between a tap 37' on resistor 37 and the terminal 11a. During dynamic braking, occasioned by tripping of the limit switch 29, the rectifier R2, because it blocks current flow therethrough in a reverse direction, i.e. from terminal 11a to tap 37', insures that all of the dynamic braking current from the armature 10 passes through the field winding 11, thereby providing full dynamic braking torque for given values of armature current, as determined by the resistance of the resistor 37.

In order to lower the hook while the limit switch is in its tripped position, at which time contacts 29a and 29b are open and contacts 29c and 29d are closed, a control circuit including a master switch 54 is provided to energize electromagnetic switches having coils 20 and 40 which close contacts 20m and 40m, respectively. This completes a motor circuit from the supply conductor 12 through the contacts 40m, the armature 10 from the terminal 10b to the terminal 10a, the limit switch contacts 29c, the field winding 11 from the terminal 11a to the terminal 11b, the brake winding 21, all or a part of the resistor 22, and the contacts 20m to the supply conductor 14. The motor is now connected as a series machine and exerts a torque in the lowering direction wherein the armature 10 rotates in the lowering direction and the current flows through the armature 10 in lowering direction and through the field winding 11 in the forward direction.

A unidirectional or rectifier circuit around the armature 10 from the armature terminal 10b to the field terminal 11a through the limit switch contacts 29d and a portion of the resistor 37 from end 37b to tap 37' and the heretofore referred to unidirectional resistor or rectifier R2, in its forward or current conductive direction also exists during series motor lowering. This rectifier circuit reduces the motor torque an amount depending upon the resistance value of the rectifier circuit.

Rectifier R2 and the portion of resistor 37, between

37' and end 37b have an ohmic value small enough in the current conductive direction to serve effectively as an armature shunt resistor in lowering out of the limit stop and still do not effect the dynamic braking torque when entering the limit switch zone. Further, the rectifier R2, by its inherent characteristics as will be later described more fully, is a higher resistance in its conductive direction when the voltage across the armature is low than when the voltage across the armature is high.

10 This rectifier circuit, including rectifier R2, being connected between the terminals 10b and 11a, provides an armature shunt which limits the lowering speed to a safe value during lowering operations with the limit switch 29 tripped.

15 It is to be noted that when the limit switch contacts 29d are open, a circuit consisting of rectifiers R1 and R2, and a portion of resistor 37 is connected in shunt with series field winding 11 in such manner that current will not flow through the rectifiers from the terminal 11a to 11b so that the rectifiers do not have to conduct heavy load currents during normal operations of the motor. Thus, much smaller and lighter weight rectifiers may be safely used since they will only conduct current while the limit switch 29 is tripped.

20 Fig. 4 shows the forward or conductive characteristic of a typical selenium rectifier such as is used for rectifier R2. It will be noted that no appreciable current will flow until a certain voltage is present across the rectifier stack. As the voltage is increased beyond this

25 certain voltage, the current conducted through the rectifier rises rapidly. This characteristic of the rectifier insures that a light hook load can be safely lowered at a reasonable rate while still protecting against overspeeding with a heavy hook load. This may be explained by considering that the rectifier circuit will act as a relatively high resistance armature shunt while the armature voltage is low corresponding to a low speed and the rectifier circuit will act as a much lower resistance when the armature voltage is higher corresponding to a higher speed.

30 The rectifier must have an inverse voltage rating sufficient to withstand the inverse voltage which is present when entering the limit switch at high speeds. As an example, a desirable rectifier for a 10 hp. 230 volt motor should have about eight standard 33 volt cells in series which will provide a momentary blocking voltage of 340 volts and provide a forward characteristic as indicated in Fig. 3. The rectifier used in this example has a rectification area of about 3 square inches per hp. for each cell and a continuous current rating about 20% of the full load motor current.

35 The herein described and illustrated control system operates as follows:

Hoisting

40 To hoist the hook 15 at one of its speeds, operation of the master switch 54 energizes the switch coils 19 and 20 to close the contacts 19m and 20m to complete a circuit extending from the conductor 12 through the contacts 19m, the contacts 29a, the armature 10, in the hoisting direction, the contacts 29b, the field winding 11 in the forward direction, the braking winding 21, the resistor 22 and the contacts 20m to the conductor 14. It is noted that the armature and field are in series across a source of voltage from line 12 to terminal 11b which is rheostatically varied in this instance by resistor 22, and that current flows in the hoisting direction through the armature and the forward direction through the field to cause rotation of the armature in a hoisting direction. Hoisting of the hook 15 at other speeds may be obtained in the same manner as described in the referred to patent.

Hoisting into limit switch

45 If the hook is hoisted high enough so that the limit switch 29 is tripped, the contacts 29a open to disconnect the motor from the power conductor 12, and thus de-

energize it, the contacts 29b open, and the contacts 29c and 29d close to complete the previously traced emergency dynamic braking circuit. Dynamic braking current generated by continued hoisting rotation of the armature now flows through armature 10 in the lowering direction from 10b to 10a, thence through contacts 29c, field winding 11 in the forward direction from 11a to 11b, through rectifier R1 in its conductive direction, resistor 37 and contacts 29d, to terminal 10b. Full dynamic braking current as generated by the armature 10 flows through the field winding since unidirectional resistor or rectifier R2 is blocking the flow of any part of the dynamic braking current therethrough and the rotation of the armature in the hoisting direction is brought to a fast, safe deceleration and smooth stop.

Lowering while limit switch is tripped

The hook 15 may be lowered while the limit switch 29 is tripped. Lowering hook 15 while the limit switch 29 is tripped is accomplished by moving the master switch 54 into any of its lowering positions, thereby effecting connection of the motor as a series machine rotating the armature in the lowering direction and exerting a downward torque. With the limit switch 29 tripped, that is, with contacts 29a and 29b open and contacts 29c and 29d closed, closure of the contacts 40m and 20m completes a motor circuit from the supply conductor 12 through the contacts 40m, the armature winding 10 in the lowering direction from 10b to 10a, the now closed contacts 29c and the field winding 11 in the forward direction from the terminal 11a to 11b. It is particularly noted that during rotation of the armature 10 in the lowering direction the current flow therethrough is in the same direction (from 10b to 10a) as the generated dynamic braking current which stopped the hoisting movement of the armature, and that the current through the field 11 is in the normal forward direction (from 11a to 11b). The resistor 22 provides a variable voltage source between line 12 and terminal 11b.

Simultaneously, an armature shunt circuit is formed in which current may flow through contacts 29d, a portion of resistor 37 from end 37b to tap 37', and rectifier R2 in its conductive direction to the terminal 11a. This circuit constitutes a rectifier circuit shunting the armature 10 and the closed contacts 29c to limit the speed of the armature. At this time rectifier R1 is blocking current flow therethrough. The rectifier circuit just described produces a slow lowering speed while the limit switch is tripped, providing a strong field and an armature shunt. To obtain adequate retarding action, the resistance of the rectifier circuit including rectifier R2 and the associated portion of resistor 37 between contacts 29d and tap 37' should be very low.

Continued lowering of hook 15 will reset the limit switch 29. If, through some failure, the limit switch 29 does not return to its normal position, the hook 15 may be lowered as far as desired. Thus when the system is used in a hoist, a heavily or lightly loaded hook 15 may be lowered safely to the ground even though the limit switch 29 remains in its tripped position.

If, as it is supposed to, the limit switch 29 returns to its normal position when the hook is moved therefrom, i.e. contacts 29a and 29b close while contacts 29c and 29d open, continued lowering or movement in the reverse direction is obtained through normal lowering operation of the master 54 as described in the referred to patent.

An alternate embodiment of the invention is obtained by substituting the circuit of Fig. 3 for its corresponding portion of the circuit of Fig. 1. In both figures like characters represent the same parts. In Fig. 3, the rectifier R2 is connected in shunt with contacts 29b and directly between terminals 10b and 11a and rectifier R1, is eliminated. Basically, the alternate circuit of Fig. 3 operates in the same manner and for the same purpose

as the circuit of Fig. 1. However, during lowering of the hook 15 while the limit switch 29 is tripped, rectifier R2 is directly in shunt with the armature and without any resistance in series with the rectifier R2. Also, since rectifier R1 is omitted, resistor 37 is connected directly between contacts 29d and terminal 11b, and provides a shunt circuit around rectifier R2 and field winding 11. However, and because of the usual large ohmic value of resistor 37, this shunt circuit has practically no effect on the operation of the system during lowering with a tripped limit switch and while contacts 29d are closed and contacts 29b are open.

Having thus described my invention, I claim:

1. A motor operating system comprising a source of direct current energy, an armature, a field winding for the armature, a rectifier adapted to conduct current in a forward direction and block current flow in a reverse direction, a resistor, a first circuit when energized by said source directing current through said armature in a hoisting direction and through said field winding in a forward direction in series to cause hoisting rotation of the armature, a second circuit effective upon deenergization of said first circuit to direct current generated by continued rotation of said armature after such deenergization through said armature in a lowering direction and through said field winding in the forward direction and through said resistor to dynamically stop rotation of said armature, a third circuit when energized by said source directing current through said armature in a lowering direction and through said field winding in said forward direction and including a rectifier circuit shunting said armature and incorporating said rectifier, said rectifier circuit constituting a variable resistance which decreases in magnitude as the voltage across the armature increases in magnitude, and switch means common to said rectifier and first and second and third circuits to selectively control said circuits.

2. A motor operating system comprising a rheostatic controlled variable voltage source of direct current energy, an armature, a field winding, a rectifier adapted to conduct current in a forward direction and block current flow in a reverse direction, a resistor, a first circuit when energized by said source directing current through said armature in a hoisting direction and through said field winding in a forward direction in series to cause hoisting rotation of the armature, a second circuit effective upon deenergization of said first circuit to direct current generated by continued rotation of said armature after such deenergization through said armature in a lowering direction and through said field winding in the forward direction and through said resistor to dynamically stop rotation of said armature, a third circuit when energized by said source directing current through said armature in a lowering direction and through said field winding in said forward direction and including a rectifier circuit shunting said armature and incorporating said rectifier, said rectifier circuit constituting a high resistance shunting said armature when the voltage thereacross is low and constituting a low resistance shunting said armature when the voltage thereacross is high, and switch means common to said rectifier and first and second and third circuits and selective to control the energization of said first and third circuits, to render said selected circuit effective, and including the control of the energization of said third circuit while the second circuit is effective.

3. A motor operating system for a direct current motor having an armature and a field winding, said system comprising a source of energy, a first normally open switch and second normally closed switch and the motor armature and a third normally closed switch, and the field winding electrically connected in series in that order across said source of energy, a fourth normally open switch shunting said armature and said third switch, a fifth normally open switch and a resistor having first and

second resistance portions shunting said third switch and said field winding, a rectifier circuit shunting said third switch and including a rectifier and said first portion of said resistor and said fifth switch, and a sixth normally open switch shunting said first and second switches and said armature, said first switch being closable to connect the motor to the source of energy to cause current to flow in one direction through said armature and field winding in series to rotate the armature in a hoisting direction, means to open the second and third switches to disconnect the motor from the source of energy and to close the fourth and fifth switches to cause current generated by continued rotation of the armature after such disconnection to flow through said fourth switch and said field winding and said resistor and said fifth switch to dynamically brake the motor, said sixth switch being closable while said fourth and fifth switches are closed to connect said motor to said source of energy to cause current to flow through said fifth switch and said first portion of said resistor and said rectifier and said field winding in said one direction and to flow through said armature and said fourth switch in another direction to rotate the armature in a lowering direction after hoisting rotation thereof has stopped.

4. The structure of claim 3 wherein said means is responsive to rotation of said armature in said hoisting direction.

5. The structure as defined in claim 3 wherein said source of energy is a rheostatically controlled variable voltage source of energy and wherein said rectifier and said first portion of said resistor effectively constitutes a high resistance shunting said armature when the voltage thereacross is low and constitutes a low resistance effectively shunting said armature when the voltage thereacross is high.

6. A motor operating system for a direct current motor having an armature and a field winding, said system comprising a source of energy and a first normally open switch and a second normally closed switch and the motor armature and a rectifier and the field winding electrically connected in series in that order across said source of energy, said rectifier being connected to pass current in a forward direction from said armature to said field winding and to block passage of current in a reverse direction from said field winding to said armature, a third normally open switch shunting said armature and said rectifier, a fourth normally open switch and a resistor shunting said rectifier and said field winding, and a fifth normally open switch shunting said first and second switch and said armature, a sixth normally closed switch shunting said rectifier, said first switch being closable to connect the motor to the source of energy to cause current to flow in a hoisting direction through said armature and in a forward direction through said field winding in series to rotate the armature in a hoisting direction, means to open the second and sixth switches to disconnect the motor from the source of energy and to close the third and fourth switches to cause current generated by continued rotation of the armature after such disconnection to flow through said armature in a lowering direction and said third switch and said field winding in said forward direction and said resistor and said fourth

switch to dynamically brake the motor, said fifth switch being closable while said second and sixth switches are open to connect said motor to said source of energy to cause current to flow through said rectifier and said field winding in said forward direction and to cause current to flow through said armature in said lowering direction to rotate the armature in a lowering direction after forward rotation thereof has stopped.

7. The structure according to claim 6 wherein said means is responsive to rotation of said armature in said hoisting direction.

8. The structure as defined in claim 6 wherein said source of energy is a rheostatically controlled variable voltage source of energy and wherein said rectifier effectively constitutes a high resistance shunting said armature when the voltage thereacross is low and constitutes a low resistance effectively shunting said armature when the voltage thereacross is high.

9. In a motor and control system combination for raising and lowering a load, a direct current motor adapted for connection to a source of power and having an armature winding and a field winding, which windings are adapted for shunt and series connection, selectively, with each other, for operation of the motor as a shunt and series machine, selectively, a limit switch mechanism having a normally closed contact means connected between a first terminal of said armature winding and a first terminal of said field winding and having a normally open contact means connected between a second terminal of said armature winding and said first terminal of said field winding, and being responsive to an elevated position of the load while the load is being raised to open said normally closed contact means and to close said normally open contact means, means for connecting a second terminal of said field winding to one side of said source of power, means for connecting said second terminal of said armature winding to the other side of said source of power for hoisting a load, and means for connecting said first terminal of the armature winding to said other side of said source of power for lowering a load when the second field terminal is connected to said one side of said source of power and while said normally closed contact means is open and said normally open contact means is closed, an acceleration resistor connected in series with said motor when said second armature terminal is connected to said source of power, the improvement which comprises a rectifier connected in parallel with said normally closed contact means and between said first armature terminal and said first field terminal to provide an armature shunt connection cooperating with said acceleration resistor to limit the lowering speed of the motor while said normally closed contact means is open and said normally open contact means is closed and until said normally closed contact means recloses.
